UNITED STATES PATENT OFFICE.

GEORGE MERZ AND HENRY KUGLER, OF FERGUS FALLS, MINNESOTA.

CAN HOLDER.

Application filed March 6, 1926. Serial No. 92,980.

This invention relates to can holders and more particularly to a can holder for maintaining a milk can in position upon the running board of a vehicle.

5 An important object of the invention is to provide a device of this character which may be very cheaply manufactured, which will be durable and efficient in service and a general improvement in the art.

10 A further object of the invention is to provide a readily manipulatable means whereby the can may be clamped in position upon the holder.

These and other objects we attain by the 15 construction shown in the accompanying drawing, wherein for the purpose of illustration is shown a preferred embodiment of our invention and wherein:—

Figure 1 is a plan view of a milk can 20 holder constructed in accordance with our invention;

Figure 2 is a section on the line 2—2 of Figure 1;

Figure 3 is a section on the line 3—3 of 25 Figure 1.

Referring now more particularly to the drawings, the numeral 10 designates a base plate, the side and rear edges of the plate being reverted upon the under surface of 30 the plate in spaced relation thereto, as indicated at 11 and 12 respectively, so as to support the base plate in spaced relation to the upper surface of an element, such as the running board R upon which the plate is arranged. The plate is provided upon its 35 under surface and more particularly upon the reverted portions 11 of the sides with clamps 13 by means of which it may be secured in position upon the running board. 40 These clamps may be of any suitable structure. The front edge of the plate is provided with a downturned flange 14, the purpose of which will presently appear.

At the center of the rear edge of the plate, 45 the plate is formed with a transversely extending slot 15 and this slot is continued through the bight 16 of the reverted portion 12 of the rear edge of the plate. The under surface of the plate has secured thereto a 50 guide 17 through which is slidably directed a bar 18, the rear end of which is upturned, as at 19, and projects upwardly through the slot 15. To the upper end of this upturned portion 19 is secured a T-head 20 which is 55 arcuately curved with the concave face arranged toward the front edge of the plate. To the

front face of the head is secured a cushioning pad 21 or the like. The forward end of the bar 18 is provided with a threaded extension 22, the forward end of which is directed 60 through an opening 23 formed in the flange 14. The forward end of this extension is indicated by a nut 24 at the rear end of a tubular member 25, the forward end of which is provided with an operating wheel 65 26. It will be obvious that by rotating the tubular member, the bar 18 may be drawn toward the forward edge of the plate, thus moving the T-head 20 toward the forward edge of the plate and toward an arcurate 70 can stop 27 secured to the forward edge of the plate by supports 28 arising therefrom. Similarly by rotating the hand wheel 26 and maintaining the inner end of the tube in engagement with the flange 14, the bar 18 75 may be caused to recede and thus to disengage from a can which is clamped between the T-head 20 and the can stop 27. The inner face of the arcurate can stop 27 is suitably padded, as at 29, so that it will not 80 mar the can, and this padding furthermore serves to provide a space for accommodating the bead B usually provided at the bottom of a milk can C.

Attention is directed to the fact that the 85 central portion 30 of the arcurate can stop 27 is curved upon a radius of less magnitude than the terminal portions 31 thereof. The curvature of the central portion is made such that this central portion fits the body of 90 a five gallon container while the terminal portions fit the body of a ten gallon container, thus permitting containers of either size to be very firmly held upon the base. 95

It will, of course, be obvious that the 100 construction hereinbefore set forth is capable of a certain range of change and modification without materially departing from the spirit of the invention and we accordingly do not limit ourselves to such specific structure except as hereinafter claimed.

We claim:—

1. A milk can holder, a base plate having at its under surface means for maintaining it in spaced relation to a support upon which it is arranged, the rear edge of the plate having a slot, the forward edge of the plate having at its upper surface an arcurate can stop opposing the rear edge of the plate, a guide upon the under surface of the plate, a bar slidable through the guide and having an upturned end operating in the slot 105 110

of the plate and an arcuate T-head carried by the upturned end of the bar and opposing the can stop.

2. A milk can holder, a base plate having at its under surface means for maintaining it in spaced relation to a support upon which it is arranged, the rear edge of the plate having a slot, the forward edge of the plate having at its upper surface an arcuate can stop opposing the rear edge of the plate, a guide upon the under surface of the plate, a bar slidable through the guide and having an upturned end operating in the slot of the plate, an arcuate T-head carried by the upturned end of the bar and opposing the can stop, the forward edge of the plate having a downwardly extending guide, the forward end of the bar having a threaded extension directed through an opening in said guide and a nut engaged with the threaded extension at the outer face of the guide.

3. A milk can holder, a base plate having at its under surface means for maintaining it in spaced relation to a support upon which it is arranged, the rear edge of the plate having a slot, the forward edge of the plate having at its upper surface an arcuate can stop opposing the rear edge of the plate, a guide upon the under surface of the plate, a bar slidable through the guide and having an upturned end operating in the slot of the plate, an arcuate T-head carried by the upturned end of the bar and opposing the can stop and means upon the under surface of the plate securing the plate in position upon the support.

4. In a milk can holder, a base plate having its side and rear edges reverted in spaced relation to the under side of the plate to provide means for supporting the plate in spaced relation to a surface upon which it is arranged, an arcuate can stop carried by the plate and affixed thereto, a slot in the plate substantially perpendicular to the can stop, a member slidable in the slot and hav-

ing at its upper end an arcuate can stop and means for securing the member in adjusted position.

5. In a milk can holder, a base plate having its side and rear edges reverted in spaced relation to the under side of the plate to provide means for supporting the plate in spaced relation to a surface upon which it is arranged, an arcuate can stop carried by the plate and affixed thereto, a slot in the plate substantially perpendicular to the can stop, a member slidable in the slot and having at its upper end an arcuate can stop and means for securing the member in adjusted position, said slot opening through the rear edges of the plate and through the bight of the reverted portion of the plate, said member slidable in the slot comprising a bar extended through guides upon the under surface of the plate and having at its forward end a nut abutting the portion of the plate whereby the bar is maintained in adjusted position, the slotting of the bight of the reverted portion of the plate permitting withdrawal of the bar through the rear edge of the plate.

6. In a milk can holder, a base plate having its side and rear edges reverted in spaced relation to the under side of the plate to provide means for supporting the plate in spaced relation to a surface upon which it is arranged, an arcuate can stop carried by the plate and affixed thereto, a slot in the plate substantially perpendicular to the can stop, a member slidable in the slot and having at its upper end an arcuate can stop and means for securing the member in adjusted position, the first named arcuate can stop having its central portion curved upon a radius of less magnitude than the terminal portions thereof.

In testimony whereof we hereunto affix our signatures.

GEORGE MERZ.
HENRY KUGLER.
